UNITED STATES PATENT OFFICE.

JOHN P. MANNY, OF ROCKFORD, ILLINOIS.

HARVESTER.

SPECIFICATION forming part of Letters Patent No. 276,847, dated May 1, 1883.

Application filed January 18, 1883. (No model.)

To all whom it may concern:

Be it known that I, JOHN P. MANNY, of Rockford, in the county of Winnebago and State of Illinois, have invented a new and useful Improvement in Harvesters, of which the following is a specification.

This invention relates to an improved construction and arrangement of the means employed to transmit motion from the driving-wheels of a harvester to the cutters, the object sought to be obtained being simplicity, compactness, and durability.

The invention consists, in substance, in arranging the main frame upon the axle between the two main wheels, and in driving the crank-shaft, which is supported on the main frame by means of two sprocket-wheels and a chain-connection, one of the sprocket-wheels being mounted between the main wheels of the machine, and the other being connected with a gear that meshes with a pinion on the crank-shaft. Motion is transmitted from the crank-shaft to the cutters through the medium of a pitman, in the usual way. The box that carries the crank-shaft is so constructed that it will also support the bevel-gear and the chain-wheel that drives the crank-shaft and hold the said gear firmly in mesh with the pinion on said shaft. This may be effected by forming a bearing or stud upon the side of the crank-box at some point between the crank-head and bevel-pinion, and mounting the bevel-gear and associated sprocket-wheel thereon. Instead, however, of thus arranging the bevel-gear between the pinion and the crank-head, the gear and the sprocket-wheel may be mounted upon a shaft passing across the head of the crank-box, the bevel-pinion in this case being placed at the proper point on the crank-shaft to engage with the bevel-gear, and the box being cut away sufficiently for this purpose. The bevel-pinion might be cast directly on the crank-head.

The invention is fully illustrated in the accompanying drawings, in which Figure 1 is a plan view of the harvester embodying the invention, Fig. 2 being a side view of the same, one of the main wheels being removed, and Fig. 3 being a front view of the crank-box and associated parts detached. Fig. 4 is a modification showing the bevel-pinion constructed

on the back of the crank-head instead of, as in Fig. 3, on the opposite end of the crank-shaft.

Referring to the drawings, Figs. 1 to 3, more in detail, A is the main frame, secured to the axle between the two main wheels.

B is a sprocket or chain wheel, mounted on the axle and driven by engagement with a backing-ratchet on the driving-wheel C; and D is the crank-shaft, rotating in the box E, secured to the side of the frame A. Projecting from the side of this box E is a post or stud, F, around which revolves a hub carrying a second chain-wheel, G, and a bevel-gear, H, the latter of which meshes with the pinion I on the crank-shaft.

J is a chain connecting the wheel B with the wheel G. K is a coupling-frame hinged at one end to a hanger, L, at the rear of the main frame, and at the other to the arm M, projecting from the crank-box E. This coupling-frame supports the shoe N, to which the finger-beam O is secured. The bar or rod which composes the frame K passes through ears on the shoe and constitutes an axis around which the finger-beam may turn in adjusting itself to the inequalities of the ground. The hinge between the main frame and the coupling-frame and between the latter and the shoe makes the finger-beam what is known in the art as a "floating finger-beam." The construction of the coupling-frame and the shoe need not be further described, as they constitute no part of the present invention and are described in detail in Letters Patent of the United States No. 216,744.

It will be observed that under the construction here shown the crank-box is so placed on the main frame as to be substantially in line with the cutting apparatus. The cutters (not shown in the drawings) will be driven by a pitman connecting the heel of the cutter-bar with the crank-pin on the crank-head P.

The above construction will be found to constitute a remarkably direct, simple, compact, and reliable connection between the driving-wheels of the machine and the cutters. It wholly avoids the necessity of the nice fittings and adjustments required when gear-connections from the main axle to the crank-shaft are used, and the straining and twisting to which

the main frame of a harvester is inevitably subjected does not lessen the power of the wheels upon the knives.

The advantage of mounting the crank-shaft 5 and the bevel-gear and chain-wheel that drive it on the same box is apparent. This mode of mounting keeps these parts rigidly and constantly in their proper relation to each other, and thus greatly lessens friction. There is also 10 a manifest advantage in connecting the coupling-frame K and the chain-wheel G with the same box or support in the manner shown in the drawings. When these parts are thus arranged the lateral pull of the cutting apparatus upon the box in one direction is largely 15 counteracted by the pull of the chain upon the sprocket-wheel on the other side of the box.

Manifestly it is not necessary that the crank-shaft occupy a position at right angles to the 20 plane of the main frame. It may be set vertical or inclined, at the option or convenience of the builder.

Fig. 4 shows in elevation a modification of the construction shown in Fig. 3. The modification consists in constructing the bevel-pinion I directly on the back of crank-head P, instead of on the opposite end of the shaft. 25

What is claimed as new is—

1. The combination, in the two-wheeled front-

cut harvester set forth, of a coupling-frame 30 hinged so as to rise and fall freely with the undulations of the ground, a crank-shaft driven by a chain-wheel and gear, all supported on the main frame in front of the main axle in rigid relation to each other, with a flexible 35 driving-connection between such chain-wheel and the main axle or the main driving-wheel, substantially as and for the purpose described.

2. The combination, in the two-wheeled front-cut harvester set forth, of a coupling-frame 40 hinged so as to rise and fall with the undulations of the ground, a gear-supporting frame connected with the main axle, a crank-box mounted on the main frame, substantially in line with the cutters, and a gear-wheel and 45 chain-wheel supported on the crank box, substantially as described.

3. The combination, in a harvester, of a box mounted on the main frame and constituting a support for the crank-shaft and for the chain-wheel and bevel-gear for operating the crank-shaft, and the coupling-frame hinged at one end to such box, substantially as described. 50
